UNITED STATES PATENT OFFICE

JOHN T. PHIPPS, OF HUNTINGTON PARK, CALIFORNIA, ASSIGNOR, BY MESNE ASSIGNMENTS, TO GLOBE OIL TOOLS COMPANY, OF LOS ANGELES, CALIFORNIA, A CORPORATION OF CALIFORNIA

ROLLER BIT

Application filed September 27, 1929. Serial No. 395,574.

This invention relates to a bit having roller cutters and pertains more especially to the pin mounting for journalling the cutters on the bit head. It has been the common practice to place roller cutters in heads by employing pins set in forked or grooved portions of the head. The pins wear rapidly due to the abrasive action of the material being drilled through, requiring replacement at frequent intervals. These pins have generally been secured in the head in such a manner that when replacement is required the entire head must be rebuilt.

It is the primary object of this invention to provide a journal pin mounting in which the pin is easily removed and replaced. A more specific object is the provision of a novel pin and lock washer construction as will be apparent from the subjoined specification.

The drawings illustrate the journal pin mounting as applied to a bit adapted to take a core, in which its advantages are particularly marked, but it is also useful in any type of bit. In the drawings, Fig. 1 is an elevation, partly in section, of a core barrel fitted with a bit or head having roller cutters journalled on pins mounted in accordance with my invention; Fig. 2 is a view similar to Fig. 1 but taken at right angles thereto; Fig. 3 is a bottom plan view on an enlarged scale of Fig. 1; Fig. 4 is a detail on an enlarged scale of one cutter and pin, similar to Fig. 1; Fig. 5 is a detail on an enlarged scale of one cutter and pin similar to Fig. 2; and Fig. 6 is a perspective view of one of the pins and washers before mounting in the head.

Referring more particularly to the drawings, the barrel or body of the tool is indicated by 8 and has a bit head 9 threadedly secured to its lower end and a threaded pin 10 at its upper end, by which it may be attached to the drill string. Within the body is the core retainer tube 11 and core catching means 12. These form no part of the present invention and will not be further described. The head is tubular being formed with a substantially cylindrical central wall 14. Cavities are formed in which are sets of roller

cutters marked 15a and 15b. The cutters are journalled on pins 16a and 16b which are mounted in bores extending in the head.

Referring to Figs. 5 and 6, it will be seen that pin 16a makes an oblique angle with the axis of the tool. Pin 16a is provided with a head 17 and a portion of reduced diameter 18. The shoulder 19 which is formed where the reduction in diameter occurs is at an oblique angle with the axis of the pin. A counterbore 20 is formed in wall 14 to receive a washer 21. The pin is inserted from the inside so that the shoulder 19 registers with the bottom of the counter bore, the washer 21 is then placed on the reduced portion in the counterbore, and the end of the reduced portion is riveted over to hold the washer in place. It may be welded if preferred. It will be evident that the pin is held against both rotary and longitudinal movement. When it is desired to remove the pin, as when it becomes worn or the cutter becomes dull, the welded or burred portion of the pin holding the washer may be cut out, which will allow the washer to come off and the pin to slip out. No cutting or damage to the head is necessary, and a new cutter can be installed and the pin replaced. The head 17 has been shown at right angles to the axis of the pin, which is desirable from a manufacturing standpoint, but it could be at any other angle that might be desirable. It will be obvious from the drawings that rollers 15b and pins 16b involve the same inventive idea. Pins 16b are substantial duplicates of pins 16a. However in the bit rollers 15a toe in and rollers 15b toe out with respect to the drilling axis of the tool.

What I claim is:—

1. A rotary drilling tool having roller cutters, comprising a body with a cavity for a cutter and provided with cavity side walls having aligned cylindrical bores for a cutter journal pin with a counterbore at one end oblique to the main axis of said bores, a cutter journal pin detachably mounted therein having a head at one end and a washer set in said counterbore and secured at its other end to said pin whereby said pin is secured against

rotary and longitudinal movement, and a cutter journalled on said pin.

2. A rotary drilling tool having roller cutters, comprising a body with a cavity for a cutter and provided with cavity side walls having alined cylindrical bores for a cutter journal pin, said bores making an oblique angle with the axis of the tool with a counter bore at the outer end oblique to the main axis to the said bores, a cutter journal pin in said bores having a head at one end and a washer set in said counterbore and secured at its other end parallel to the drilling axis of and flush with the outer surface of said body, whereby said pin is held against rotary and longitudinal movement, and a cutter journalled on said pin.

3. A rotary drilling tool having roller cutters, comprising a body with a cavity for a cutter and provided with cavity side walls having alined cylindrical bores for a cutter journal pin with a counterbore at the outer end oblique to the main axis of said bores, said bores making an oblique angle with the axis of the tool, a cutter journal pin having a head at one end and a reduced portion at its outer end, the shoulder adjacent said reduced portion being at an oblique angle with the axis of said pin, said pin being positioned in said bores so that said shoulder is parallel with the drilling axis of the tool, a washer set in said counterbore and secured on said reduced portion against said shoulder whereby said pin is held against rotary and longitudinal movement, and a cutter journalled on said pin.

In witness that I claim the foregoing I have hereunto subscribed my name this 7th day of September, 1929.

JOHN T. PHIPPS.
